(57) **CLAIM**

The ornamental design for a pull box, as shown and described.

DESCRIPTION

FIG. 1 is a perspective view of one embodiment of a pull box in a closed state;

FIG. 2 is a perspective view of the pull box of FIG. 1 in an open state;

FIG. 3 is a first side view of the pull box of FIG. 1;

FIG. 4 is a second side view of the pull box of FIG. 1;

FIG. 5 is a first end view of the pull box of FIG. 1;

FIG. 6 is a second end view of the pull box of FIG. 1;

FIG. 7 is a top view of the pull box of FIG. 1; and,

FIG. 8 is a bottom view of the pull box of FIG. 1.

Broken lines show portions of the pull box that form no part of the claimed design.
